RADIO CIRCUIT

Application filed October 19, 1932. Serial No. 638,549.

This invention relates in general to improvements in radio circuits and particularly to the power supply for the filaments and plates of vacuum tubes employed in such circuits.

The prime object of this invention is the provision of a multi-stage vacuum tube radio circuit adapted to be energized by either direct or alternating current.

10 A further object of this invention is the provision of a radio circuit of this type in which the filaments or heating electrodes of the vacuum tubes are supplied directly with alternating or direct current or through a resistance.

15 A still further object of this invention is the provision of a circuit of this type in which all of the filaments are connected in series and energized directly from a direct or alternating current power circuit.

20 A still further object of this invention involves a radio circuit employing a plurality of multi-electrode vacuum tubes in combination with a vacuum tube rectifier so arranged 25 and connected that the plate voltages for all the vacuum tubes may be applied from either a direct or alternating current power circuit.

These and other objects as will appear from the following disclosure are secured 30 by means of this invention.

This invention resides substantially in the combination, construction, arrangement, relative location of parts and circuit connections all as will be described in detail below.

35 Referring to the drawings,

Fig. 1 shows the invention embodied in a system employing indirectly heated tubes in the output stages;

40 Fig. 2 shows the invention embodied in a system employing filamentary tubes in the output circuit;

45 It is the most general practice at the present time in supplying energy for the cathodes and anodes of multi-electrode vacuum tubes and radio circuits from a power circuit such as a house lighting circuit of 110 volts. At the present time the apparatus employed is usually called the "power pack" which must be designed for use on direct or alternating 50 current power circuits but which is not de-

signed for use on both. It is the general purpose of this invention to provide circuit connections and rectifiers which will permit of the use of direct or alternating current without necessitating any changes in the apparatus. For example, an alternating current power pack of the type now used cannot be employed in connection with the direct current source because of the use of transformers through which a steady current, of course, 55 cannot act. In order to fully understand this invention reference will now be made to the drawings.

Although a circuit has been shown in the drawings employing three stages of radio frequency amplification, a detector and two stages of audio frequency amplification it will, of course, be apparent from the following disclosure that the principles of this invention may be applied to many other forms 60 of radio circuits. In addition, although a vacuum tube rectifier system of one form has been disclosed the principles of this invention may be applied to other known forms. The circuit is shown employing so called 65 screen grid vacuum tubes in the radio frequency circuit indicated by the reference numerals 1, 2 and 3. It is likewise apparent that three-electrode tubes could be used. All 70 of the vacuum tubes shown in this circuit have been disclosed as indirectly heated cathode vacuum tubes, but here again tubes could be used with the proper precautions employing the filaments as cathodes. The detector indicated at 4 is a three-electrode vacuum tube 75 employing an indirectly heated cathode, as are the two audio amplifier tubes 5 and 6. Similar vacuum tubes 7 and 8 are used in the rectifier. The input for the circuit is connected to the lead 9 of vacuum tube 1 which 80 lead is grounded to a relatively high resistance as shown. The screening grids of vacuum tubes 1, 2 and 3 are shown all connected together and connected through a high resistance 21 to the positive terminal of the plate 85 voltage supply. The common lead for these grids is also shown grounded through the variable resistance 22 and through a by-pass condenser. The indirectly heated cathode of 90 these three tubes are all connected together 95

100

and the common lead is grounded through a resistance 23 of such value that the voltage drop through it will place the cathodes at the proper positive potential with respect to the grids of the respective tubes, this resistance being shunted by the by-pass condenser 24. The indirectly heated cathode of vacuum tube 4 is connected to the negative lead of the heater element and grounded as shown at 25. 10 All of these tubes are connected together in the usual manner by radio frequency transformers which have their secondaries tuned by a variable condenser. The indirectly heated cathodes of the vacuum tubes 5 and 6 are grounded through resistances of such value that the voltage drop will produce the proper positive potential on the cathodes with respect to their respective grids. The terminals 30 are supplied to which the output of 15 the last audio stage is connected to the sound reproducing device. Since vacuum tubes 7 and 8 have both grids and plates indicated at 10 and 11 respectively, they have been interconnected and connected to a common lead 12 which is the positive lead and which is connected to a suitable connector 53 by which connection is made to the power source. The filaments or heaters of all the vacuum tubes are shown connected in series and to wire 12 20 through the resistance 14. This resistance 14 is of a relatively low value and, of course, is proportioned so as to supply the proper voltage to the filaments of all the vacuum tubes and its size will, of course, depend upon the 25 voltage of the power source and the number of filaments or heaters connected in series. The plate electrodes of vacuum tubes 1, 2, 3, 5 and 6 are all connected together by a common lead 19 which, in turn is connected by wire 30 30 17 to a suitable point in the filter system comprising the resistance 16, choke coil 26 and condensers 15. Of course any suitable arrangement of resistance, inductance and capacity may be employed in the filter. The 35 plate electrode of vacuum tube 4 is connected by wire 18 to the filter at a point where the proper voltage is supplied thereto. The return connection for the filaments is through wire 20 to the filter as shown. One input 40 terminal of the filter is connected by a wire to the connector 13 which is the negative side of the line. The other input terminal of the filter is connected by a wire 27 to both of the cathodes of the vacuum tubes 7 and 8. 45 50 The operation of this circuit with either alternating or direct current is at once apparent. With either alternating or direct current supplied through connector 13 all of the heaters or filaments of all of the vacuum tubes are energized through the properly proportioned resistance 14. The current will flow through wire 12, resistance 14, through the heaters or filaments of vacuum tubes 8 and 7 respectively, through the heaters or filaments of vacuum tubes 3, 2 and 1

respectively, through the heaters or filaments of vacuum tubes 6, 5 and 4 respectively, and thence back through wire 20 and the filter to the negative side of the connector. When alternating current is used to heat the cathodes an indirectly heated cathode is of course better than a directly heated cathode since it is easier to eliminate any hum or disturbance produced by the alternating current. The plate current for the various tubes is supplied by the rectifier comprising tubes 7 and 8 in conjunction with the filter. The current for this supply, whether direct or alternating, is provided as follows. Current flows through wire 12 to the anodes 10 and 11 of tubes 7 and 8. The output of these tubes is supplied through wire 27 to the filter and from the filter through wires 17 and 19 for all of the tubes except tube 4. For tube 4 the plate is supplied through the filter and wire 18. The filament return lead for all of the plate circuits is through wire 20 and the filter back to the connector. When direct current is employed the output of the filter is substantially a steady current while the pulsating current delivered by the rectifier when alternating current is used is further smoothed out by the filter.

With proper precautions the invention may be embodied in a system employing directly heated filamentary tubes in the output circuit. Such a system is shown in Fig. 2, wherein there is employed a radio frequency amplifier tube 31 comprising an electron emitting cathode 32 which is insulatingly spaced from its heater 33. The signals are impressed by means of the tuned input transformer 34 across the control grid 35 and the cathode 32. A suitable grid biasing resistance 36 being provided. The screen grid 37 is connected through a suitable resistance 38 to a positive terminal of the rectified current and is shunted by a condenser 39 in the usual manner. The tube 40 is an ordinary three-element tube of the indirectly heated cathode type, wherein the cathode 41 is insulatingly spaced from the heater 42. A suitable grid bias 43 is provided for enabling the tube 42 to act properly as a detector, the signals being impressed upon this detector from the output of tube 31 through the tuned coupling circuit in accordance with standard practice. The detected output is fed, by means of audio frequency transformer 44 across the control grid 45 and the cathode 46 of a first stage amplifying tube 47. Here again the cathode 46 is insulatingly spaced from the associated heater 48.

The output of the amplifier 47 is impressed across a pair of output tubes 49 and 50. These tubes may be of the ordinary directly heated filamentary cathode type, these cathodes being indicated by the numerals 51 and 52. The coupling transformer 53 is provided with a pair of independent secondary windings 54

- and 55. The winding 54 has one terminal connected to the electrical midpoint of the filament 51, this latter connection being effected by means of a resistance 57 connected 5 across the said filament. Likewise the secondary winding 55 has one terminal connected to the control grid 58 and the other terminal connected to the midpoint of the filament 52. The output is taken off from the 10 two anodes 59 and 60 by means of a coupling coil 61 in accordance with the principles of so-called class B amplification. The operating voltages for the various anodes are derived from a suitable supply such as commercial current supply mains either of the 15 A. C. or D. C. type. The lower main 62 is connected to the anode 63 of a vacuum tube rectifier 64. This rectifier as shown is of the indirectly heated cathode type, wherein the 20 cathode 65 is insulatingly spaced from its heater 66. The other main 63 is connected in series through the filaments 52, 51, 48, 42, 38 and 66, and thence through the limiting resistance 67. Thus the said filaments are 25 energized directly by alternating current. The potentials that are applied to the various anodes are derived from the rectified current passing between the anode 63 and the cathode 65. The ripples in this current being smoothed out by a suitable filter network 30 as shown. The manner of functioning of the system of Fig. 2 is substantially the same as that of Fig. 1, and is capable of use with either direct or alternating current supplies.
- 35 From the foregoing disclosure it will be apparent that I have devised radio circuits employing tubes which can be energized by either direct or alternating current in accordance with certain principles of construction and operation. Those skilled in the art will readily appreciate that these principles of construction and operation may be embodied in various forms of practical circuits 40 without departing from the spirit and scope of this invention, and I do not, therefore, desire to be limited to the disclosure as given for purposes of illustration, but rather to the scope of the appended claims.
- 45 This application is a continuation in part of abandoned application Serial No. 398,601.
- 50 What is claimed is:
1. In a radio circuit of the type described, the combination comprising a plurality of 55 coupled multi-electrode vacuum tubes including indirectly heated cathodes and anodes, said cathodes being provided with heater means insulatingly spaced therefrom, a rectifier having a heatable filament and an 60 anode, a circuit including all of said heater means and said filament adapted to be energized by direct or alternating current, a filter connected in the output of said rectifier, and connections from the filter and the anodes of 65 said vacuum tubes whereby a substantially 70 constant potential is supplied thereto either from a direct or alternating current source.
  2. In a radio circuit of the type described, the combination comprising a plurality of 75 coupled multi-electrode vacuum tubes including indirectly heated cathodes and anodes, said cathodes being provided with heater means insulatingly spaced therefrom, a rectifier having a heatable filament, a circuit including a resistance, all of said heater 80 means and said filament adapted to be energized by direct or alternating current, a filter connected in the output of said rectifier, and connections from the filter and the anodes of said vacuum tubes whereby a substantially constant potential is supplied thereto either from a direct or alternating current source.
  3. In a radio circuit of the type described, the combination comprising a plurality of 85 multi-electrode vacuum tubes coupled together to form a combined detector and amplifier, said vacuum tubes having indirectly heated cathodes and anodes, said cathodes being provided with heater means insulatingly spaced therefrom, a thermionic rectifier likewise having a heater element and an anode, a circuit between all of said heaters including a resistance whereby they may be directly connected to either a direct or alternating current house lighting circuit, a filter system connected in the output of said thermionic rectifier and connections between said filter and all of the plate electrodes of 90 said multi-electrode vacuum tubes whereby a substantially steady potential may be impressed thereon when the rectifier is energized by either direct or alternating current.
  4. In a radio circuit of the type described, comprising a combined radio frequency amplifier, detector and audio frequency amplifier employing a plurality of multi-electrode vacuum tubes coupled together, each of said tubes having at least an indirectly heated 95 cathode and an anode, said cathode being provided with heater means insulatingly spaced therefrom, a thermionic rectifier having a heatable cathode and an anode, all of the heaters for said cathodes being connected in series, means whereby said heaters can be directly connected to either a direct or alternating current source, a filter connected to the output of said rectifier, connections between the anode of all the said multi-electrode vacuum tubes and the filter, and connections for the anode of said thermionic rectifier whereby either direct or alternating current may be directly impressed thereon.
  5. In a radio circuit of the type described, the combination comprising a plurality of 105 vacuum tubes coupled together to form a combined detector and amplifier, indirectly heated cathodes in all of said vacuum tubes, heaters for said cathodes, insulatingly spaced 110 therefrom, anodes in all of said vacuum tubes,

1 a thermionic rectifier having cathodes and
2 anodes, connections including all of said
3 heaters and the cathodes in said rectifier in-
4 cluding a resistance whereby alternating cur-
5 rent or direct current may be directly sup-
6 plied thereto, a filter system in the output of
7 said rectifier, connections between all of the
8 anodes of said multi-electrode vacuum tubes
9 and said filter, and connections for the anodes
10 of said rectifier whereby either direct or
11 alternating current may be supplied directly
12 thereto.

13 6. In a radio circuit of the type described,
14 the combination comprising a plurality of
15 vacuum tubes coupled together to form a
16 combined detector and amplifier, indirectly
17 heated cathodes in all of said vacuum tubes,
18 heaters for said cathodes, anodes in all of
19 said vacuum tubes, a thermionic rectifier hav-
20 ing indirectly heated cathodes, heaters for
21 said cathodes and anodes, connections in-
22 cluding all of said heaters including a resist-
23 ance whereby alternating current or direct
24 current may be directly supplied thereto, a
25 filter system in the output of said rectifier,
26 connections between all of the anodes of said
27 multi-electrode vacuum tubes and said filter,
28 and connections for the anodes of said recti-
29 fier whereby either direct or alternating cur-
30 rent may be supplied directly thereto.

31 7. In a radio circuit of the type described
32 the combination comprising a plurality of
33 vacuum tubes coupled together to form a
34 combined detector and amplifier, indirectly
35 heated cathodes in all of said vacuum tubes,
36 heaters for said cathodes insulatingly spaced
37 therefrom, anodes in all of said vacuum tubes,
38 a thermionic rectifier having an electron
39 emitter, a heater filament for said emitter, a
40 circuit including all of said heaters and the
41 filament of said rectifier and a resistance,
42 means whereby alternating current or direct
43 current may be directly supplied said circuit,
44 a filter system in the output of said rectifier,
45 connections between all of the anodes of said
46 multi-electrode vacuum tubes and said filter,
47 and connections for the anode of said recti-
48 fier whereby either direct or alternating cur-
49 rent may be supplied directly thereto.

50 8. In a radio circuit of the type described
51 the combination comprising a plurality of
52 vacuum tubes coupled together to form a
53 combined detector and amplifier, indirectly
54 heated cathodes in all of said vacuum tubes,
55 heaters for said cathodes, anodes in all of
56 said vacuum tubes, a thermionic rectifier hav-
57 ing an indirectly heated cathode and an
58 anode, heaters for all said cathodes, and a
59 heater for said rectifier cathode, a circuit in-
60 cluding all of said heaters and a resistance,
61 means whereby alternating current or direct
62 current may be directly supplied to said cir-
63 circuit, a filter system connected to all said recti-
64 fiers, connections between all of the anodes
65 of said multi-electrode vacuum tubes and
